UNITED STATES PATENT OFFICE.

OLIVER McCARTHY, OF MERIDEN, CONNECTICUT, ASSIGNOR TO THE
MERIDEN BRITANNIA COMPANY, OF SAME PLACE.

DESIGN FOR A COFFIN-HANDLE.

SPECIFICATION forming part of Design No. 22,535, dated June 13, 1893.

Application filed May 15, 1893. Serial No. 474,356. Term of patent 7 years.

To all whom it may concern:

Be it known that I, OLIVER McCARTHY, of Meriden, in the county of New Haven and State of Connecticut, have invented a new Design for a Coffin-Handle; and I do hereby declare the following, when taken in connection with the accompanying drawing and the letters of reference marked thereon, to be a full, clear, and exact description of the same, and which said drawing constitutes part of this specification, and represents a face view.

This invention relates to a design for coffin-handles, and the design consists in the configuration and ornamentation as hereinafter described and shown in the accompanying illustration.

Each of the socket-plates of my newly designed coffin-handle, has a raised, ribbed rectangular panel A, having the appearance of being composed of convex moldings mitered together. This panel is surrounded at a lower plane than its face, by an elaborate band in the rococo style of decoration, and composed of shell-forms B, and long scrolls C, the upper and lower portions of the band, and the sides of the band, corresponding to each other. A projection D, having a smooth surface, is located in the center of each of the panels A. Drops E depending from the said projec-

tions, are provided upon their outer faces with 30 ornamentation of a similar character, and consisting of shell-like forms F, scrolls G, and beads H. The central portion I, of the handle-bar is made plain, the bar terminating at each end in ornate tips, the surface of which 35 is broken by bands J, J', J² and J³. The narrow space between the bands J and J' contains an ornamentation of beads K. The concaved space between the bands J' and J², is 40 filled in with alternate sheaf-like forms L, and rope-like forms M. The convexed space between the bands J² and J³ is occupied with panels N, inclosing double shell-like ornaments O, the extreme end of the tip lying outside of the band J³ being occupied by an ornate band of scrolls P, placed side by side.

I claim—

The design for a coffin-handle as herein described and shown in the accompanying illustration.

In testimony whereof I have signed this specification in the presence of two subscribing witnesses.

OLIVER McCARTHY.
